UNITED STATES PATENT OFFICE.

MAGNUS EFRAIM MELLGREN, OF GOTTERBORG, SWEDEN.

APPARATUS FOR HEATING THE AIR ADMITTED TO THE CARBURETORS OF PETROL ENGINES.

Application filed January 27, 1923. Serial No. 615,275.

To all whom it may concern:

Be it known that I, MAGNUS EFRAIM MELLGREN, a subject of the King of Sweden, residing at Gottenborg, Sweden, have invented a new and useful Improvement in Apparatus for Heating the Air Admitted to the Carburetors of Petrol Engines; and I do hereby declare the following to be a full, clear, and exact description of the same.

It is well known that the starting of motors in which is used petrol or other volatile fuel often incurs difficulties during cold weather. This drawback is especially prominent in automobile motors, airplane motors, boat motors and the like, which have been exposed to the cold. The primary air is often so cold that so much of the sprayed petrol cannot be evaporized as is necessary to form an ignitable or explosive mixture, and it is thus difficult or impossible to produce the first explosions. The use of a lamp or open fire for heating of parts of the motor is generally prohibited by strict regulations, and the procuring and employment of large quantities of hot water is in many cases very difficult to obtain.

The invention relates to an apparatus by means of which it is possible in an easy and simple manner to heat the primary air to such a temperature that a good evaporizing of the fuel is obtained thus effecting an easy starting of automobiles or other motors, which in this manner can be kept running until the motor is sufficiently heated. According to the invention a special heating body is used for this purpose in connection with an aluminothermic heating cartridge or a similar source of heat which can develop heat in a closed space without access of atmospheric air and without gaseous reaction products arising.

A modification of the invention is shown in the drawings, where

Figure 1 is a sectional view of the apparatus,

Figure 2 a side view of the same,

Figure 3 a sectional view of a detail,

Figure 4 diagrammatically the mounting of the apparatus on an automobile,

Figure 5 another modification,

Figure 6 a detail of the same seen from below,

Figure 7 a section through the inner part of a further modification,

Figure 8 a side view,

Figure 9 a top view of the said modification, and

Figure 10 a detail.

The apparatus consists preferably of an outer casing 1 of metal, such as aluminum or bronze, inside of which is positioned a heating body 2 of copper or some other suitable heat conducting metal that has a high melting point. The heating body 2 has formed in its top a dish-shaped cavity 10, which is closed preferably by a cover 3 that is held in clamping engagement with the casing by means of a curved supporting member 4 connected at its opposed ends to the sides of the casing by the threaded bolts 4'. A screw 5 extends through a central opening in the member 4 and engages the top of the cover 3 for securing the latter in clamping position on the casing. The cavity 10 is adapted to receive a heating cartridge, as shown in dotted lines in Figure 1. The heating body 2 has preferably a downward annular flange 11 which surrounds and is spaced away from a longitudinally extending tubular member 12, preferably formed integral with the casing 1. The lower end of the tubular member 12 terminates in an exteriorly threaded nipple 13 by means of which the casing may be removably connected to the intake opening for air of the carburetor. The wall of the casing 1 is provided with a series of lateral openings 14, through which air may be admitted into the interior of the casing. The air on its way through the casing sweeps over the surface of the part 11 and takes the path as indicated by the arrows in Figure 1, finally being conducted by the nipple 13 to the carburetor. The sectional area for the air taken in through the apparatus is relatively large, which is of importance partly for the achievement of a sufficient heating of the air during its passing through the apparatus and partly in order to reduce as much as possible the resistance against the motion of the air through the apparatus, it being well known that it is injurious to the good effect of a carburetor that the admission of primary air is throttled more than absolutely necessary.

On the cover 3 is mounted a stud 7, Figure 3, into which can be inserted a handle 9 which is retained by a spring-actuated hook 8 as indicated and serves for the introduction of means for igniting the cartridge. When the apparatus is to be used the cover

3 is removed and in the cavity 10 is placed a heating cartridge provided with an igniting fuse, whereupon, the cover is then replaced and clamped tightly in position by the screw 5. The handle 9 is preferably formed with a longitudinal bore 9' which aligns with the opening in the stud 7 on the cover 3 so as to permit the insertion of any suitable igniting means for igniting the cartridge, such as an ignited vesuvian. The cartridge upon being ignited quickly reacts and in a short time heats the body 2 to a temperature, the height of which is contingent on the heat capacity of the body and the amount of heat developed by the cartridge. By the suitable selection and carrying out of these conditions, it is possible to obtain the desired heat of the body 2, which, however, is not sufficiently great to ignite the mixture of air and petrol vapor if the same should "fire back" through the carburetor.

Figure 4 shows diagrammatically a method of mounting the apparatus on an automobile. As it is generally prohibited through police regulations to have devices in which is used open fire arranged within the motor-cover, a piping 15 leading forward is mounted on the carburetor, and the apparatus 1 is connected with the same in front of the radiator 16. The air intake of the carburetor 17 is connected by a pipe 18 in known manner with a perforated sleeve 19 surrounding the exhaust pipe 20, and between the pipes 15 and 18 is placed a three-way cock 21 by means of which the stud of the carburetor for taking in air can be connected either with the pipe 15 or with the pipe 18.

When the motor is to be started in cold weather, the three-way cock is turned in such a manner that the pipe 15 is connected with the apparatus, and a heating cartridge is placed and ignited in the casing 1. In the course of some few seconds the motor can easily be started, and when the exhaust pipe 20 has become heated, the three-way cock 21 is turned in such a manner that the carburetor is now taking in air through the sleeve 19 and the pipe 18. If the motor is desired to develop higher power, the three-way cock 21 can be constructed in such a manner that it can be placed in an intermediate position in which the carburetor takes in air from the pipe 15 as well as from the pipe 18, thereby reducing the temperature of the primary air, by mixing the same with fresh cold air, since the apparatus in the meantime has become so cool that the air taken in through the pipe 15 is now also lowered in temperature. It is well known that in order not to reduce the amount of combustible mixture admitted per cycle at full load of the motor the primary air of the carburetor should not be heated more than absolutely necessary. The mounting

of the three-way cock and the pipe 15 is thus also advantageous when driving in hot weather.

Figure 5 shows a modification of the apparatus which is meant for being inserted in the intake pipe for air of the carburetor. The casing 1 has here a couple of studs 23 placed opposite to one another in which the ends of the intake pipe 24 are secured, and the copper body 11 carries a number of ribs 22 shown in Figure 6 which can be heated and impart heat to the air current sweeping over the same.

The modification shown in Figures 7 to 9 is also meant for being inserted in the air intake piping but differs from that shown in Figures 4 to 6 in that the inner body 2 with cover 3 and clamp 4 are removable as a unit. The body 11 is preferably made of copper and has circumferential ribs 22', the lower ones of which are provided with apertures 27 in order to permit the air in addition to passing through the casing 1 and sweeping along the body 2 to also pass under the bottom of the same. The body 2 is preferably inserted in the casing 1, in the manner as shown in Figure 8, and fastened in the same by means of spring leaves 24' pivoted at 26, the ends of the studs 25 serving for turning the said spring leaves by hand and are adapted to snap into an annular groove 26' in the cover 3.

This apparatus is used in the following manner.

When the motor is to be started in cold weather the spring leaves 24' are turned to the sides as indicated in dotted lines in the right side of Figure 9, and the parts shown in Figure 7 are removed from the motor. A heating cartridge is introduced in the cavity 10, the cover 3 is then replaced and the cartridge is brought to reaction or ignited while the parts are removed from the engine so that any danger of setting the petrol on fire is avoided. The device is now replaced in the housing 1 as shown in Figure 8 and after one or two minutes the motor can easily be started.

During the warm weather or when no hot air is needed the parts shown in Figure 7 can be removed and substituted by a cover 3' which can be perforated, if desired, as shown in Figure 10.

Having thus fully described my invention I claim as new and desire to secure by Letters Patent:

1. A heater of the class described having in combination a casing, a heating body mounted in said casing and having a cavity therein, a heating cartridge adapted to fit in said cavity, a closure for said cavity detachably connected to said casing, said closure having an opening therein, a handle having a longitudinal bore in alignment with said opening, and means for detach-

ably connecting said handle to the closure.

2. A heater of the class described having in combination a casing, a heating body mounted in said casing, and having a cavity formed in the outer end thereof, a heating cartridge adapted to fit in said cavity, a closure for said cavity mounted on said casing, a curved supporting member pivotally connected to the sides of said casing and having a central opening therethrough, said casing having a series of ports in the wall thereof for conducting air to said heating body, and a bolt threaded in said opening and adapted to engage said closure for detachably securing the latter to the casing.

3. A heater of the class described having in combination a casing provided with a longitudinally extending central tube, a heating body mounted in said casing and having a depending annular flange encircling said tube, said body having a cavity in the top thereof, a heating cartridge adapted to fit in said cavity, a closure for said cavity, and means connected to said casing for detachably securing the closure in position.

4. An apparatus for heating air admitted to the carburetor of an internal combustion engine having in combination a casing, a heating body mounted in said casing and having a cavity therein, a heating cartridge in said cavity, means detachably connected to said casing for closing said cavity, and means for connecting the interior of the casing with the air intake of a carburetor.

5. An apparatus for heating air admitted to the carburetor of an internal combustion engine having in combination a casing, a heating body mounted in said casing and having a cavity therein, a heating cartridge in said cavity, means detachably connected to said casing for closing said cavity, said cartridge being adapted to react in a closed space and form non-gaseous reaction products, a cover detachably connected to said casing for closing said cavity, and means connecting the casing with the air intake of the carburetor.

6. An apparatus for heating air admitted to the carburetor of an internal combustion engine having in combination a casing, a

heating body mounted in said casing and having a cavity therein, a heating cartridge in said cavity, means detachably connected to said casing for closing said cavity, and means for connecting the interior of the casing with the air intake of the carburetor, said means comprising a pipe connecting the apparatus with the air intake of the carburetor and the exhaust of the motor, and a valve on said pipe for selectively communicating the apparatus with the carburetor and the exhaust.

7. An apparatus for heating air admitted to the carburetor of an internal combustion engine comprising a casing connected with the air intake of the carburetor, a heating body having a cavity and composed of metal having a high conductivity for heat and a comparatively high melting point, a heating cartridge fitted in said cavity and adapted when ignited to heat said body, a cover, means for detachably securing the cover in position, the said body, cover, and securing means being adapted to be removed from the casing as a unit, and means for removably securing the said unit to the casing.

8. An apparatus for heating air admitted to the carburetor of an internal combustion engine comprising a casing connected with the air intake of the carburetor, a heating body having a cavity and composed of metal having a high conductivity for heat and a comparatively high melting point, a heating cartridge fitted in said cavity and adapted when ignited to heat said body, a cover, means for detachably securing the cover in position, the said body, cover and securing means being adapted to be removed from the casing as a unit, said cover having an annular groove therein, and yieldable means on said casing and engaging said groove for detachably securing the said unit in the casing.

In testimony whereof I have affixed my signature in presence of two witnesses.

MAGNUS EFRAIM MELLGREN.
